(57) **CLAIM**

The ornamental design for a swab, as shown and described.

DESCRIPTION

FIG. 1 is a perspective view of a swab showing my new design.

FIG. 2 is another perspective view of a swab showing my new design.

FIG. 3 is a side view of a swab showing my new design.

FIG. 4 is another side view of a swab showing my new design.

FIG. 5 is an end view of a swab showing my new design; and, FIG. 6 is another end view of a swab showing my new design. The broken lines shown in FIGS. 1 through 6 illustrate portions of the swab that form no part of the claimed design.
